DEEP WELL MOTOR PUMP

Horace M. Hallgarth, Galva, Kans.

Application August 25, 1937, Serial No. 160,811

2 Claims. (Cl. 103—46)

My invention relates to deep well motor pumps and has for its chief object a motor system comprising a pair of cylinders, each having a piston and rod, the rods upwardly extending, the cylinders having an oil well with pump rod therebetween, and means to connect the upper ends of the piston rods to the pump rod, and a third cylinder horizontally disposed and having a piston and rod positioned therein and power means 5 to actuate the piston reciprocatingly and a pipe connecting said cylinders, the pipe and cylinders between their respective pistons being filled with oil or the like, by which means displacement of the oil reciprocatingly by the piston of the last 10 said cylinder will act upon the pair of cylinder pistons in like manner as actuating means for the oil well pump, and the said horizontally positioned cylinder may be spaced a considerable distance from the well without impairing seriously 15 the capacity of the motor.

A further object of my invention is to provide an auxiliary supply tank for the motor system, said tank being connected to the pipe line and adapted to supply fluid automatically as required, the tank having a check valve to close 20 against compression in the motor system, said valve to open under vacuum strain to supply deficiency of fluid therein.

A still further object of my invention is to provide a motor pump that will work in connection 25 with pump jacks commonly employed in oil fields, the hookup being such that the gravity pull of the polish rod of one well will assist in raising the pump rod of another well and vice versa alternately.

These and other objects will hereinafter be more fully explained, reference being had to the accompanying drawings forming a part of this specification and in which like characters will 30 apply to like parts in the different views.

Referring to the drawings:—

Fig. 1 is a side view of the motor, parts being removed for convenience of illustration.

Fig. 2 is a plan view of Fig. 1.

Fig. 3 is a reduced side view of the reciprocating cylinder, showing its relative position to the crank shaft and adjacent oil well and beam pumper.

Fig. 4 is an enlarged sectional view of the auxiliary fluid supply tank, showing the valve.

Fig. 5 is an enlarged view of the yoke, parts being removed for convenience of illustration.

Fig. 6 is an enlarged sectional view of the yoke end connection taken on line 6—6 in Fig. 5, looking in direction of the arrows.

Fig. 7 is an enlarged detail of the connection between the cylinder and cross-head guide.

Fig. 8 is a side view of an alternate method of operating the crank shaft through the medium of a worm gear arrangement, parts being removed 5 for convenience of illustration.

Fig. 9 is an end view of Fig. 7, parts being removed for convenience of illustration.

My invention herein disclosed consists of a compression cylinder 1, said cylinder being secured to a foundation 2, by means of anchor rods 3 extending there-around and inward into the foundation that is preferably made of concrete.

The said cylinder has a conical portion at one end thereof as at A, and to which a pressure pipe 15 10 connects, the other end of said cylinder has a head 4 secured fluid tight therein and axially bored to receive a stuffing box 5, through which a piston rod 6 will slidably engage.

Secured to the end of said rod within the cylinder is a piston 7 snugly engaging peripherally within said cylinder with a smooth running fit, for the purpose later described.

Secured to the outer end of said piston rod is a cross-head 8, that slidably engages in a track 9, 25 20 said track being aligned with the cylinder longitudinally and in parallelism with the axis thereof and secured thereto by flanges 10 and 11 respectively that are bolted together, the said track being made of a pipe and having a plurality of 30 openings 12 cut therethrough as means to gain access to the said rod connection and stuffing box.

As heretofore stated pressure pipe 3', that is connected to the frustum end of the conical portion joined to cylinder 1, is means to conduct 35 fluid from cylinder 1 to a pair of cylinders 13, connecting with the same at the lower extremity thereof by laterals B respectively. Said laterals being secured to the end of said pressure pipe 3' 40 are means to equalize the oil pressure in said pair of cylinders, and transmit power intermittently to raise pistons 14, later described, and permit the same to move downward freely as the oil movement is effected by the piston in cylinder 1, in its reciprocating movement.

Each of said cylinders 13 has a piston 14 and tubular rod 15 connected thereto, said rods extending upward and outward through their respective cylinder heads 16, functioning as guides for the rods in their reciprocating movement, all 50 of which constituting a hoist for a pump rod.

It will be understood that the pump rod 17 of an oil well 18 is centrally positioned between the said pair of cylinders, the upper end of said rod being secured to a yoke 19 substantially as shown 55

in Figs. 1 and 5, the said yoke being connected at its opposite ends to said piston rods 15. The said rods each have a lug 18 adapted to seat in a pocket 20 positioned in each end of the yoke, and secured therein by a pin 21 extending through the walls of the pocket and passing through an elongated slot 22 transversely crossing the lug, by which means rocking movement of the yoke will not affect vertical alignment of 10 said rods in their movement, such movement being due to unequal hoisting power of the cylinders.

It will also be understood that the pipe line 3' and cylinder 1 will be solidly filled with oil, including the space below pistons 14, and being so filled the said pair of pistons 14 will be forced upward as piston 7 is moved toward the conical end of its respective cylinder 1, the movement being through the medium of a crank 23 formed in a 20 shaft 24 that is power actuated. The said crank and cross head 8 are joined by a connecting rod 25, one end of which is hingedly connected to the cross head 8 while the other end is pivotally secured to the crank, as shown in Figs. 1 and 2. 25 The said shaft has a second crank 26 positioned at 90 degrees from the first said crank.

The last said crank 26 is connected to one end of a walking beam 27 of a pump jack, by a connecting rod 28, as rocking means for said beam that is centrally pivoted on a standard 29, while the other end of said beam carries a pump rod 30 of another oil well functioning as a hoist of the pump rod and by which means the gravity pull of one pump rod will function as a counter-balance to assist in raising the other rod and vice versa alternately.

As a means to supply shortage of fluid in the pipe line and cylinders above described, I have arranged and vertically positioned an auxiliary tank 31 on said pressure pipe 3', preferably in close proximity to cylinder 1 as shown in Figs. 1 and 3, the function of which is as follows:

The said tank is filled with oil which is retained therein by a spring tensioned valve 32 positioned in the bottom thereof, the said valve closing under pressure while the motor is in action and solidly filled with oil, but should the system be partially deprived of its oil for any reason, such deficiency will be supplied as the vacuum will open said valve 32, causing an inflow 50 of oil from the tank automatically sufficient to fill the motor system.

The said auxiliary tank has a glass gauge 33 positioned on the side thereof to determine the quantity of oil contained therein. There is also arranged on the cap of said tank, a U shaped weatherproof vent 34 to avoid a vacuum as the oil recedes.

I have placed a plurality of apertures 35 in rods 15, adjacent their respective pistons and a U shaped vent 36 in each head of said rods, by which means vacuum and compression is abated during reciprocation of the pistons.

In Figs. 8 and 9 is shown a means to turn the said crank shaft, said means comprising a worm 65 37 in mesh with a worm gear 38, said worm and gear being within a housing 39, that is separably arranged and secured together by screws 40 engaging through ears 41 respectively, the said housing being fluid tight and mounted on a base 70 42 that is anchored to a foundation 43 through the medium of bolts 44. The said worm gear has a shaft 45 axially secured therein, said shaft being trunnioned in bearings 46 that are likewise

anchored to the upper extending legs C of said foundation, and the said shaft having secured to each outer end thereof the cranks 23 and 26, the said cranks being positioned at right angle to each other and having connected thereto the 5 said connecting rods 25 and 28.

It is understood that the said worm is mounted on shaft 45 that extends to a power actuating means therefor, said means not shown in the drawings, and that such other modifications may 10 be employed as lie within the scope of the appended claims.

Having fully described my invention, what I claim as new and desire to secure by Letters Patent is:—

1. In a deep well motor pump, the combination of a pair of head hoisting cylinders, for one of a pair of oil wells, each of which has a pump rod, each cylinder having a piston and a hollow apertured rod to avoid compression in the upper 20 stroke of the pistons and means to connect the rods to one of said pump rods, of a compression cylinder and pressure pipe line for the hoists, said cylinder and pressure line being filled with oil, of a piston positioned in the end of the compression cylinder opposite its pipe connection, said piston having a rod, and power actuating means therefor to move the piston to the other end of the said compression cylinder and cause return of the same which in turn effects 25 the movement of each hoist piston simultaneously to actuate the pump rod, of an auxiliary tank having a check valve adjacent the pressure line as automatic means to supply oil to the pressure line and compression cylinder as the oil exhausts 30 therefrom, of a piston rod and guiding means 35 therefor, of a shaft having two cranks rotatable therewith and mechanical power to turn the shaft, means to connect one of the cranks to the piston rod as actuating means therefor, and means to connect the other crank to the other pump rod for the purpose specified.

2. In deep well motor pumps, in combination with the pump rods of two wells, one pump rod being operated by a hydraulic jack and the other by the conventional walking beam, the hydraulic jack of its respective well comprising the combination of a pair of head hoisting cylinders, each of which has a piston and a hollow apertured rod to avoid compression in the upper stroke of the pistons and means to connect the rods to its respective pump rod, of a compression cylinder and pressure pipe line for the hoists, said cylinder and pressure line being filled with oil, of a piston positioned in the end of the compression cylinder opposite its pipe connection, said piston having a rod, and power actuating means therefor to move the piston to the other end of the said compression cylinder and cause return of the same which in turn effects the movement of each hoist piston simultaneously to actuate the pump rod, of an auxiliary tank having a check valve adjacent the pressure line as automatic means to supply oil to the pressure line and compression cylinder as the oil exhausts 40 therefrom, of a piston rod and guiding means 45 therefor, of a shaft having two cranks rotatable therewith and mechanical power to turn the shaft, means to connect one of the cranks to the piston rod as actuating means therefor, and means to connect the other crank to the walking beam of the other well for the purpose specified.

HORACE M. HALLGARTH.
